BLANCHING MACHINE

Freeman M. McBeth, Harrisburg, Pa., assignor to
Macbeth Engineering Corporation, a corpora-
tion of Pennsylvania

Application June 9, 1944, Serial No. 539,527

5. Claims. (Cl. 99—443)

1

This invention relates to the art of food processing and is principally concerned with apparatus for conditioning vegetables or fruits preparatory to their cooking or dehydration.

A primary object of the invention is to provide an improved apparatus for blanching vegetables, such as potatoes, carrots and the like, or fruits, after they have been sliced or otherwise cut up, which is so designed that such operation may be performed expeditiously and continuously to supply the blanched material in a constant flow to a frying or dehydrating apparatus.

Another object is to provide in such an apparatus means for conveying material being processed at adjustably variable levels with respect to the surface of a confined body of treating liquid, whereby blanching may be effected through immersion or by the agency of steam arising from the surface of the treating liquid.

A further object is to provide, in association with a treating liquid container, a material conveyor having a major portion thereof adjustable with respect to the remainder whereby to dispose said major portion at the horizontal or at varying degrees of inclination relative thereto.

A still further object is to provide a blanching apparatus having a circulatory treating liquid system including means for establishing different levels of the liquid in relation to a material conveyor for selective procurement of immersion or steam blanching.

Other objects of the invention will be apparent to those skilled in the art. These include a novel conveyor drive mechanism and conveyor construction.

With the above objects in view, the invention comprises the novel arrangement, construction, and combination of parts hereinafter described and claimed. It is to be understood that the structural details and arrangement of the component parts of the embodiment herein disclosed may be varied as desired within the scope of the invention as claimed, and that the illustrated disclosure is not to be considered as being the only means by which the invention may be reduced to practice.

In the accompanying drawings like reference characters indicate like parts throughout the several views.

Figure 1 is a side elevation of an apparatus constructed in accordance with the present invention, parts being broken away.

Figure 2 is a front or inlet end view thereof.

Figure 3 is a top plan view of the apparatus.

2

Figure 4 is a rear end view of the motor, pump, and transmission assembly.

Figure 5 is a fragmentary top plan view of the inlet end portion of the treating tank with conveyor removed.

Figure 6 is a vertical section substantially on the line 6—6 of Figure 5.

Figure 7 is a section taken on the line 7—7 of Figure 1.

10 Figure 8 is a fragmentary sectional view illustrating details of the elevator conveyor drive.

Figures 9 and 10 are, respectively, side elevation and horizontal sectional views of the conveyor hinge assembly.

15 As shown, the invention comprises a blanching tank 15 of elongated rectangular form and provided with a sloping bottom 16 that inclines downwardly from the inlet end 17 to the outlet end 18. The end plate 18 comprises a partition

20 that forms the front wall of a washing tank 19 formed as a rearward prolongation of the blanching tank. The height of the partition is less than that of the tank side walls 20 and 21 to provide clearance for a portion of the material conveyor 23 to be described.

25 Sediment collecting on the sloping bottom 16 of the tank is discharged from its low end to a disposal pipe 22 having a valve control 23. In order to assist discharge of sediment, a transverse spray head 24 is disposed at the inlet end of the tank bottom. This spray head communicates through a pipe connection 25 with a liquid supply pipe 26 which leads to a T-coupling 27 that, in turn, connects with a riser pipe 28 leading to 30 an upper spray head or nozzle 29 disposed substantially in horizontal register with and above the spray head 24 at approximately midway of the height of the tank. The respective connections 28 and 25 are controlled by valves 30 and

35 31. At the rear or outlet end of the tank an outlet pipe 32 controlled by a valve 33 leads from the tank to the suction side of a pump 34 provided with a force side riser 35 that connects with an elbow 36 which couples to the inlet pipe line

40 37. A motor 37 is employed to actuate the pump which, when in operation with all appropriate valves open, establishes a circulatory system for the body of treating liquid 38 within the tank. Normally, this circulation is maintained from 45 the upper spray head 29 longitudinally through the tank to the outlet 32, and as the outlet 32 is lower than the inlet spray head a downwardly inclined current is created which not only assists in maintaining material being treated upon the conveyor, to be described, but also acts to propel

50 55

sediment downwardly and rearwardly upon the sloping bottom of the tank. A steam coil 39 is disposed longitudinally within the tank adjacent the bottom thereof to provide means for heating the liquid in the tank.

The blanching tank has disposed therein an endless belt conveyor of reticulated or open mesh construction that extends longitudinally from the inlet end to the outlet end of the tank. The conveyor belt extends between side chains 40, preferably of the linked roller type, and is attached thereto by means of cross rods 40a. The upper flights of the chains travel along the foot flanges 41 of angle-iron side bars 42 that connect at their forward ends with a transverse end bar 43 to provide a conveyor frame. At the forward end of the frame slideable bearings 44, equipped with adjusting screws 45, mount conveyor chain sprockets 46, and substantially midway of the frame the side bars carry attached hangers 47 which support and guide the lower flights of the conveyor chains to maintain them substantially in parallel relation to the upper flights and to prevent sagging of the lower flight of the conveyor into contact with the steam coils 39. The conveyor belt is provided with appropriately spaced, parallel, transverse cleats 48. The conveyor belt, designated generally by the reference character 49, has a major longitudinal forward section A that is capable of bodily movement in a vertical arc in hinged relation to an upwardly and rearwardly inclined rear section B which extends over and rearwardly beyond the partition 18 at the rear end of the blanching tank, to overhang the washing tank 19.

The rear section B of the conveyor trains over side chain sprockets 50 and 51 mounted, respectively, at the forward and rear ends of a fixed frame that is suitably secured in the tank and which has angle-iron side bars 52 with foot flanges 53. The side bars of the fixed frame are similar in construction to the side bars 42 of the movable conveyor section A, and constitute longitudinal rearward extensions thereof. As best illustrated in Figures 9 and 10, each side bar 52 of the fixed frame has secured rigidly to its forward lower end a horizontally disposed forwardly projecting plate 54 provided with an outward lateral pintle lug 55 engaged in an apertured ear 56 carried as a lateral offset by a plate 57 attached to the movable frame bar 42. By this means the inner or rear end of the movable frame carrying the conveyor section A is hinged to the forward end of the fixed frame carrying the conveyor section B. In order to guide the conveyor chains at the hinge connection between the two frames, the lower forward end of each fixed frame side bar 52 is vertically enlarged to provide a bearing portion 58 for an idler 59 that overrides the side chain.

The movable frame of the conveyor section A is adjustable along a vertical arc through the medium of a downwardly and rearwardly inclined material distribution plate 60 that is vertically adjustable on the inlet end wall 17 of the blanching tank. This plate is of perforate material and extends transversely for the full width of the conveyor. The lower inner end of the plate is slightly upturned and extends inwardly over and above the forward end of the conveyor, so that material to be treated slides down the distribution plate from a supply source, not shown, and is discharged evenly over and upon the conveyor. At its side edges the plate 60 has depending flanges 61 which are pivotally con-

nected at their lower ends by means 62 to the side portions of the forward end assembly of the movable conveyor frame. As best shown in Figures 1, 3 and 6, the upper end of the plate 60 is provided with a pair of upwardly extending, vertically slotted hanger straps 63 which slide upon the adjacent end wall 17 of the tank. Suitable securing means, which may be a nut and bolt assembly 64 carried by brackets on the upper end of the tank end wall 17 and disposed through the vertical slots in the straps 63, enables a vertical adjustment of the distribution plate 60 to raise or lower the forward end of the hinged section A of the conveyor to or from the dotted line position shown in Figure 6.

At one side the blanching tank is provided with a clean-out closure 65 and with a lateral liquid level control chamber 66 opening to the tank interior. The bottom 67 of the chamber 20 determines the low surface level L of liquid in the blanching tank when steam blanching is being carried out. The chamber has an outlet 68 at its bottom in communication with a discharge pipe 69, and an outlet 70 at its top that 25 communicates with an extension of the discharge pipe. A control valve 72 in the outlet 68 establishes either the high level H or the low level L for the treating liquid. The high level is maintained when immersion blanching is carried 30 out.

Material delivered from the rear section B of the conveyor into the liquid contained in the washing tank 19 is carried therefrom by an endless bucket elevator 74. The elevator belt 35 is attached to side chains trained over drive sprockets. Figure 8 illustrates one such sprocket 75 in operative engagement with a chain 76, so arranged that both flights of the chain are positively driven. The sprocket shaft 77 is journalled in a bearing block 78 that is secured between the elevator guides 79 on a bracket 80 fixed to the top of the washing tank. Power is supplied to the drive shaft pulley 81 by a belt 82 connected to an intermediate drive pulley 45 assembly 83 mounted on a frame 84 in rear of the washing tank. The assembly 83 is driven from a belt drive 85 leading to the transmission 86 which in turn has a drive connection 87 with the motor 37. The sprocket drive pulley 81 also has a belt drive 88 in operative connection with the driven sprocket 51 at the rear end of the conveyor.

As shown best in Figure 8, the down flight of the elevator chain 76 rides upon its adjacent 55 guide and is held against the guide by the sprocket 75. The up flight of the chain 76 rides over the outer face of its guide 79 and engages the sprocket where it plays through an aperture in the guide. The chain is trained beneath an exterior guide shoe 89 into positive engagement with the sprocket. By this means the sprocket 75 has a positive drive engagement with both flights of the elevator chain 76.

When the apparatus is employed for immersion blanching, the blanching tank is filled with treating liquid up to the high surface level H and the movable section A of the conveyor is adjusted to the full line position shown in Figures 1 and 6. The material to be treated is 70 dropped down the distribution plate 60 onto the conveyor belt and is there carried upwardly and rearwardly through the liquid bath until discharged into the washing tank 19 where it is picked up by the bucket elevator and carried to a point of further treatment, not shown. When

the apparatus is employed for steam blanching the liquid is brought to the low surface level L and the hinged section A of the conveyor is raised to the horizontal dotted line position shown in Figure 6. The hinge point of the conveyor is so related to the low liquid level as determined by the control chamber outlet 68 that when the conveyor section A is disposed in horizontal position its upper flight will be entirely out of the liquid. Steam is then generated by raising the temperature of the liquid to the boiling point by means of the steam coils, and the material being processed is exposed to the steam during its entire extent of travel on the conveyor.

A deflector baffle 90 extends substantially horizontally inwardly from the tank end 17 above the lower spray head 24 so that when this spray head is used to clear sediment from the tank bottom the injected liquid is directed along the sloping tank bottom.

It will be apparent that the speed of travel of the conveyor may be varied to regulate the treating period for material being processed, and that by appropriate manipulation of the various valves the circulation of the treating liquid through the tank may be adjustably related to the conveyor speed, or may be cut off entirely. Furthermore, by adjusting the hinged section of the conveyor at various heights the duration of immersion may be varied as desired to suit the nature of the material being processed.

Having thus described the invention, what is claimed is:

1. A blanching machine comprising in combination a tank for the reception of a treating liquid, a material conveyor disposed longitudinally within said tank and having a receiving portion movable at its forward end through a vertical arc for adjustment relative to the surface level of liquid in the tank, said conveyor having a discharge portion continuous with the receiving portion and upwardly and rearwardly inclined over the rear end of the tank, a washing tank beneath the rear end of said discharge portion of the conveyor, a material elevator in said washing tank, a closed circulatory system for the tank liquid including a pump, a driving means, and an operative connection between said driving means and said conveyor, elevator, and pump.

2. In a blanching machine, a tank for the reception of treating liquid, a conveyor supporting frame disposed longitudinally within said tank and hinged at its inner end for movement in a vertical plane, an endless belt material conveyor on said frame, means for operating said conveyor, liquid injecting means adjacent the free end of said conveyor and spaced above and below the same, and a horizontal baffle plate extending from a wall of the tank between elements of said injecting means.

3. A blanching machine comprising a tank for

the reception of a treating liquid, a material conveyor disposed longitudinally therein and including a fixed portion and a movable portion hinged thereto at one end, a supporting member extending between the other end of said movable conveyor portion and one vertical wall of said tank, means connecting said supporting member to the said other end of said movable conveyor portion, means connecting said supporting member to the said vertical wall of said tank, one of said connecting means being vertically adjustable whereby said movable conveyor portion may be disposed in a horizontal or inclined position, and means for establishing and maintaining different surface levels for the tank liquid.

4. A blanching machine comprising a tank for the reception of a treating liquid, a material conveyor disposed longitudinally therein and including a fixed portion and a movable portion hinged thereto at one end, a supporting member extending between the other end of said movable conveyor portion and one end wall of said tank, means connecting said supporting member to the said other end of said movable conveyor portion, means connecting said supporting member to the said end wall of said tank for vertical adjustment thereon whereby said movable conveyor portion may be disposed in a horizontal or inclined position, and means for establishing and maintaining different surface levels for the tank liquid.

5. A blanching machine comprising a tank for the reception of a treating liquid, a material conveyor disposed longitudinally therein and including a fixed portion and a movable portion hinged thereto at one end, a material distributing plate extending over and connected to the other end of said movable conveyor portion, means connecting said distributing plate to one end wall of said tank for vertical adjustment thereon whereby said movable conveyor portion may be disposed in a horizontal or inclined position, and means for establishing different surface levels for the tank liquid.
